(57) **CLAIM**

The ornamental design for a container cover, as shown and described.

DESCRIPTION

FIG. 1 is a perspective view of a container cover showing my new design;

FIG. 2 is a front elevation view thereof, the rear elevation view being a mirror image thereof;

FIG. 3 is a right side elevation view thereof, the left side elevation view being a mirror image thereof;

FIG. 4 is a top plan view thereof; and,

FIG. 5 is bottom plan view thereof.

The broken lines shown in the drawings are for illustration purposes only and form no part of the claimed design.
